UNITED STATES PATENT OFFICE

146,367

DESIGN FOR A DOG PLAY STRAP

John S. Mahler, Highland Park, Ill.

Application January 12, 1946, Serial No. 125,509

Term of patent 14 years

(Cl. D34—15)

To all whom it may concern:

Be it known that I, John S. Mahler, a citizen of the United States, residing at Highland Park, in the county of Lake and State of Illinois, have invented a new, original, and ornamental Design for a Dog Play Strap, of which the following is a specification, reference being had to the accompanying drawing, forming a part thereof.

In the drawing:

Fig. 1 is a plan view of a dog play strap showing my new design;

Fig. 2 is a side elevation thereof;

Fig. 3 is an end elevation thereof; and

Fig. 4 is an enlarged cross section thereof taken on the line 4—4 of Fig. 1.

I claim:

The ornamental design for a dog play strap, as shown.

JOHN S. MAHLER.
